UNITED STATES PATENT OFFICE.

ADAM A. SERVA, OF CANTON, OHIO, ASSIGNOR TO THE UNITED ELECTRIC COMPANY, OF CANTON, OHIO, A CORPORATION OF OHIO.

BRUSH AND HANDLE FOR VACUUM CLEANERS.

Application filed September 23, 1922. Serial No. 590,113.

This invention relates to rotary brushes and handle bails for use upon vacuum cleaners or similar devices arranged to be moved to and fro upon the floor by means of a 5 pivoted handle, a rotary brush being mounted in the cleaner for removing surface litter; and the objects of the improvement are, to provide an efficient means for rotating the brush from a traction wheel of the cleaner 10 and to provide simple means for pivoting the handle bail upon the cleaner for holding the handle bail in adjusted positions, and for attaching the handle to the handle bail.

The above and other objects may be attained by constructing the device as illustrated in the accompanying drawings, in which—

Figure 1 is a side elevation of a vacuum cleaner embodying the improvements;

20 Fig. 2, a section on the line 2—2, Fig. 1;

Fig. 3, a section through the bearing for the handle bail on the opposite side from that shown in Fig. 2;

Fig. 4, a perspective view of the segmental 25 plate which receives the clamping screw of the handle bail;

Fig. 5, a perspective view of the spring plate which cooperates with the clamping bolt for holding the handle bail in the in- 30 operative position.

Fig. 6, a section through the handle socket and the lower end of the handle;

Fig. 7, a detail perspective view of the segmental plate and spring plate, part of the segmental plate being broken away for the 35 purpose of illustration.

Similar numerals of reference indicate corresponding parts throughout the several figures of the drawings.

40 For the purpose of illustrating the application of the improvements to a portable machine, a vacuum cleaner of any usual type is illustrated, and comprises the fan casing 1, having the usual suction shoe or cleaning nozzle 2 at its forward end and supporting the motor casing 3, the discharge neck 4 being located at the rear end of the casing and communicating with the usual dust collecting bag 5, a handle bail 6 being pivotally connected to opposite sides of the casing and provided with the operating handle 7 for the purpose of manipulating the machine to and fro upon the floor.

50 Traction wheels 8 are provided on each side in rear of the ends of the cleaning nozzle

so that the same can be tilted upward or downward by lowering or raising the rear end of the machine, a rear castor 9 being employed for limiting the downward movement.

65 Each extremity of the handle bail is provided with a bearing opening 10 journaled upon a headed bushing 11, said bushing being mounted upon a stud 12 having the preferably enlarged threaded portion 13 inserted into a suitable threaded bore 14 in the adjacent side of the sweeper casing.

70 The head 15 of the bushing is grooved as at 16 to receive the cotter pin 17, which is passed through the stud 12 and the outer extremity 75 of said stud is threaded as at 18 to receive the locking nut 19.

75 It will be seen that a very desirable construction of journal bearing is thus provided as the inner end of the bushing 11 impinges 80 the adjacent side of the casing, the bail being journaled between the casing and the head of the bushing preventing the same from being squeezed or pinched against the side of the casing by a tightening up of the nut 19.

85 For the purpose of holding the handle bail in different adjusted positions a segmental plate 20 is located over the stud 12 upon one side of the casing and connected to the casing as by the screws 21, said plate having an arcuate slot 22 which receives the clamping bolt 23 carried by the handle bail, a lock washer 24 and wing nut 25 being provided upon the outer end of the clamping bolt for the purpose of clamping the handle bail to the segmental plate.

90 It has been found preferable to form the plate 20 of a hard metal and to place a washer 26 between the head of the clamping bolt and the segmental plate, this washer being formed of copper or other soft metal, in order to tightly clamp the handle bail in any adjusted position.

95 A spring plate 27 is mounted over the stud 12 between the plate 20 and the adjacent side 100 of the casing, one of the screws 21 being preferably located through said spring plate.

105 A tang 28 is formed upon said spring plate, having the rounded socket 29 and the angular extremity 30, over which the head of the clamping bolt may ride to permit the same to seat itself in the socket 29 which is so located that the handle bail will be held in the inoperative position.

110 A socket 31 is provided with a grooved rib

32 connected to the middle portion of the handle bail as by rivets 33, and a stem 34 is located through a longitudinal bore in the tapered lower end of the handle 7 and held therein as by the transverse pin 35, the extremity of said stem extending through the aperture 36 in the bottom of the socket and being threaded to receive the wing nut 37, a lock washer 38 being interposed between the bottom of the socket and the wing nut.

It will be obvious that a simple and efficient means is thus provided for attaching the handle to the handle bail, the tapered end of the handle being drawn down tightly into the socket as the wing nut is tightened on the threaded stem.

I claim:—

1. In combination with a vacuum cleaner, a threaded stud upon each side thereof, a headed bushing mounted upon each stud, a handle bail journaled upon the bushing and

a nut upon the stud for tightening the bushing against the side wall of the cleaner.

2. In combination with a vacuum cleaner, a threaded stud upon each side thereof, a headed bushing mounted upon each stud, a cotter pin located through the head of each bushing and through the stud, a handle bail journaled upon the bushing and a nut upon a stud for tightening the bushing against the side wall of the cleaner.

3. In combination with a vacuum cleaner, a stud fixed to each side thereof and provided with a threaded outer portion, a bushing mounted upon each stud and having a head at its outer end, a handle bail having its end portions journaled upon said bushing and a nut upon the threaded portion of each stud engaging the head of the bushing and clamping the inner end of the bushing against the side of the cleaner.
